SHOPPING BAG

Fritzi Klopfenstein, Weston, Conn., assignor to Interstate Bag Company, Inc., Walden, N.Y., a corporation of Virginia

Filed Feb. 10, 1966, Ser. No. 989

Term of patent 14 years

(Cl. D58—2)

Fig. 2.

Fig. 1.

FIGURE 1 is a perspective view of a shopping bag showing my new design, the side not shown being the same as that shown; and

FIGURE 2 is an end elevational view thereof, the same design being repeated on the other end.

The ornamentation has been omitted from the end panel in FIGURE 1 for convenience of illustration.

I claim:

The ornamental design for a shopping bag, as shown and described.
